LATCH-ACCOMMODATING KEEPER UNIT

William J. Pinard, Manchester, N. H.

Application February 24, 1945, Serial No. 579,552

2 Claims. (CL 292—340)

1

This invention relates to so-called knob-controlled and actuated night latches such as are employed on domestic doors, and the like, for use in conjunction with regular key-controlled locks, and the purpose of the invention is to provide an improved keeper unit which has certain structural advantages, but which is usable in connection with virtually any and all knob-equipped projectible and retractible latch units.

In the drawings I have shown a more or less conventional latch unit merely to bring out its association and coaction with the keeper unit. However, and as above implied, such structural novelty as exists herein is devoted to the keeper unit by itself.

Briefly, the improved keeper unit is characterized by a hollow box-like casing for reception of the projectible and retractible latch bolt, said casing having a back plate, end plates and a front plate, the latter serving as the abutment and retainer for the latch bolt, there being special reinforcing flanges opposed to the back plate and connected with the end plates, and said back plate also having an adapter extension with reinforcing webs.

The object of the invention is to provide a keeper unit of the aforementioned type which can be successfully applied to the door jamb or frame so that it will project therefrom laterally to coact with the latch unit, the construction and method of attachment of said keeper unit being such as to provide for rigidity and to promote ease of manufacture, simplicity in design and mode of attachment, the latter step attainable without likelihood of breakage of the keeper unit or damage to the door jamb or frame on which it is mounted.

Not only is the keeper unit applicable to the door frame to project outwardly therefrom, but is susceptible of being submerged and sunk in a mortise formed in the door jamb, this to adapt it for use in structures wherein the door itself recedes into the frame and the latch unit is therefore substantially flush with the coacting surface of the door frame.

Other features and advantages will become more readily apparent from the following description and the accompanying illustrative drawings.

In the drawings, wherein like reference characters are employed to designate like parts throughout the several views:

Figure 1 is a fragmentary elevational view showing a portion of a door, a door frame, a knob-equipped latch unit to the right on the

2

door, and the improved keeper unit on the door frame.

Figure 2 is a view of Figure 1, looking downwardly on top of the two units, that is, the latch unit and the keeper unit, parts being in section.

Figure 3 is a view like Figure 1, but showing the door frame of such form that the door recedes or sinks into same, the keeper unit being sunk in said door frame with one wall exposed.

Figure 4 is a view like Figure 2, but taken on the basis of Figure 3 looking down on top of the parts.

Figure 5 is a section on line 5—5 of Figure 4.

Figure 6 is a detail plan view of the keeper unit by itself.

Figure 7 is an elevational view observing one side, which may be called the back plate, with the extension and reinforcing webs.

Figure 8 is a view like Figure 7 observing the opposite or what might be called the front side or face of said keeper unit.

Figure 9 is an elevational view in which the observer sees the back, front and marginal end walls or plates, thus bringing out the construction of the unit from all sides, taken in conjunction with Figures 6 to 8, inclusive.

Referring now to the drawings by distinguishing reference characters and with reference to Figures 1 to 5, inclusive, it will be seen that the door is denoted at A, the door jamb or frame at B, the knob-equipped latch unit at C, and the improved keeper unit at 10. The parts A, B and C are obviously old. Referring further to the latch unit, this comprises the usual rectangular casing D with a marginal attaching flange E, a night latch or safety device F and usual knurled operating knob G. The beveled nose latch bolt is indicated at H, this being on the usual spring-actuated plunger J. The plunger is operated by the knob through suitable mechanism (not shown). Thus, it will be seen that the latch unit C is old and no part of this invention.

The invention has to do with the keeper unit 10. This is brought out best, it is believed, in

Figures 6 to 9, inclusive. Here, we observe that the main shell 11 is in the form of a rectangular hollow construction and is characterized by what we will call a back wall 12 having screw holes 13, this being provided with an integral extension or attaching flange 14 in turn provided with triangular connective webs and reinforcing elements 15. The flange is also provided with screw holes 16 which serve in a manner to be hereinafter described. The end walls are denoted at 17, these connecting with the

10. This is brought out best, it is believed, in

Figures 6 to 9, inclusive. Here, we observe that the main shell 11 is in the form of a rectangular hollow construction and is characterized by what we will call a back wall 12 having screw holes 13, this being provided with an integral extension or attaching flange 14 in turn provided with triangular connective webs and reinforcing elements 15. The flange is also provided with screw holes 16 which serve in a manner to be hereinafter described. The end walls are denoted at 17, these connecting with the

50. This is brought out best, it is believed, in

55. This is brought out best, it is believed, in

latch bolt abutment wall 18. The front wall is actually made up of a pair of cut-away extensions or flanges 19 formed integral with the end walls 17 and said abutment wall 18.

The keeper unit is applied either as shown in Figures 1 and 2, or in Figures 3 to 5. In Figures 1 and 2, the door A closes flush with the door jamb B and therefore the parts C and 10 are in somewhat customary positions for coaction with each other. More specifically, the keeper unit 10 is then fastened to the door frame by way of the special adapter flange 14. Thus, screws 20 are passed through the screw holes 16 for fastening the keeper unit in place. It is so positioned that the flanges 19 are on opposite sides 15 of the projected latch bolt H, the latter being adapted to abut the abutment plate 18 between said flanges 19. If desired, this plate 18 can be thickened or reinforced (not shown) at this point for strength. When the door closes below the surface of the door jamb, as shown in Figures 3 and 4, the door comes to rest against the wall K of the rabbet, the remaining edge of the door opposing the right angularly disposed wall L of the same rabbet. This wall L is therefore mortised in order to accommodate the then substantially embedded keeper unit. It is necessary to form a cavity to accommodate the rectangular shell of the keeper unit and also to provide counter grooves into which the flange 14 and reinforcing webs 15 slip in place. This is brought out in Figure 4. At this time, instead of the flange 14 serving to accommodate the screws, the wall, that is, the back wall 12, serves to accommodate the screws 21, thus anchoring the unit 35 securely in place.

A careful consideration of the foregoing description in conjunction with the invention as illustrated in the drawings will enable the reader to obtain a clear understanding and impression 40

of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. A keeper unit of the class described comprising a substantially rectangular hollow shell embodying a rectangular back wall, laterally disposed end walls, an outer latch bolt abutment wall adjoining the back and end walls, and a pair of flanges in alignment with each other and connected with the end and outer abutment walls, said flanges being spaced apart and opposed in parallelism to said back wall, and said back wall being provided with a right angular extension formed integral therewith, the extension constituting an attaching flange, said back wall and flange being provided with screw-accommodation holes.

2. A keeper unit of the class described comprising a hollow shell embodying a flat back wall, integral right angularly disposed end walls, and outer latch accommodation and abutment wall at right angles to and adjoining said back and end walls, a pair of flanges in alignment and in the same plane with each other and connected with said end and outer abutment walls, said back wall being provided with an integral right angular extension, said extension constituting an attaching flange, said flange being connected to the inner end portion of said back wall, said back wall and said flange both being provided with screw accommodation holes, and substantially triangular reinforcing webs connected with and located between the end portions of said flange and back wall.

WILLIAM J. PINARD.
